Primary Examiner — Mark A Goodwin*(74) Attorney, Agent, or Firm* — Duane Morris LLP(57) **CLAIM**

The ornamental design for an aerator, as shown and described.

DESCRIPTION

FIG. 1 is an isometric view of the aerator showing our new design;

FIG. 2 is a side view of the aerator;

FIG. 3 is a side view of the aerator opposite the side view of the aerator shown in FIG. 2;

FIG. 4 is a top side view of the aerator; and,

FIG. 5 is a cross-sectional view of the aerator taken along line 5-5 in FIG. 4.
